ROAD HEATING MACHINE

Frederic L. van Allen and Alfred T. King, Philadelphia, Pa., assignors to Galen Wood, Media, Pa.

Application September 17, 1928, Serial No. 306,364

6 Claims. (Cl. 126—271.2)

This invention relates to road heating machines.

It is well known that in repairing the asphalt surface of a street, removal of the old surface to be replaced is facilitated by intensive heating. Intensive heating also facilitates the excavation of frozen ground. The application of intense heat to successive areas in re-surfacing an asphalt street or to spots of a road surface that are irregularly scattered, requires much changing of position of the machine as these areas and spots are successively treated. The rapidity with which the machine can be handled in changing its position from one road spot to another is an item bearing upon the expense of the operations.

Therefore it is one of the objects of our invention to provide a road heating machine of such construction and arrangement of its functioning elements in connection with its supporting frame as will permit of turning the machine in as small a space as possible and as rapidly as possible. In this connection, one of the features of our invention is the mounting of the frame of the machine upon a tractor, such as a Fordson, or a short caterpillar tractor at three points as in three point suspension.

Another object is to adapt the heating device to be quickly raised or lowered by the operator from where he sits to operate the tractor.

Another object of our invention is to have the heating device directly connected with the hood which covers the spot to be heated and thus get a more intense application of heat.

These and other objects will be described in detail with reference to the drawings, in which—

Figure 1 is a side elevation of a road heating machine embodying our invention;

Figure 2 is a top plan of the machine shown in Figure 1;

Figure 3 is a top plan of the heating hood, partly broken away, to show internal construction, and

Figure 4 is a vertical section of Figure 3.

In Figures 1 and 2 the frame 25 of the machine is shown mounted upon the tractor 26 and is attached thereto at three places, two of which are at 27 and 28 where U bolts 29 hold the frame on top of rear axle housing 30. The third place of attachment is at the center of the front axle beam 31 where the supporting hook 32 is secured thereto by means of bolt 33 which passes through the shank end of the hook 32 and the frame member 34, the latter lying between the shank and the hook end with the hook hanging

on the bolt 33. This hook 32 is fixed at the lower central part of the U portion 34 of the frame 25.

Upon the rear end of the frame 25 is mounted the fuel tank or container 35. At the front end of the frame 25 the hood 36 is freely suspended by means of cables 37, 38, 39 and 40. Mounted on top of the hood 36, centrally positioned, is the circular fire box or combustion chamber 41 lined with fire brick 42, this constitutes a furnace, and has an opening 43 leading into the cavity of the hood 36 (see Figures 3 and 4). The hood 36 is made of special heat resisting metal sheets 44 stiffened by angle irons 45 which are spaced from the plates 44 by washers 46, through which pass bolts 47 securing the angle irons 45 to the plates 44. The sheets 44 are bent down to form the skirt 48 and legs 49 are provided to hold the skirt 48 off the ground or pavement, thus affording a space 49a beneath the skirt 48 for the escape of the hot gases.

Suspended below the fire box 41 within the hood 36 is the square spreader plate 50, the edges of which are parallel respectively to the four vertical sides forming the skirt 48. This spreader plate 50 is formed as an inverted pyramid with the apex at 51 and with flaring flanged portions 52 which are parallel with the roof plates 44 of the hood 36 and is adjustably spaced and hung thereunder on bolts 53. This spreader plate 50 serves to transmit as well as radiate heat downward and to deflect and spread the hot gases which pass between it and the roof of the hood 36.

In order to protect the tractor and the power plant of the machine from the hot gases issuing from beneath the hood 36 we provide a screen 54, attached to a U frame 55 which is pivoted at the ears 56 and 57 mounted on the hood 36. This U frame 55 rests upon the top of hood 36 but is free to be lifted so as to raise the screen 54 independent of the hood 36. When the hood 36 is raised the U frame 55 is raised with it. In order to steady the hood 36 with respect to the frame 25 we provide a spacing frame 58 loosely, but securely jointed together and securely bolted to the hood 36 and the beam 31 of the tractor.

The hood 36 is raised by means of four cables 37, 38, 39 and 40, which pass over the respective pulleys 59, 60, 61 and 62. These cables are fixed together in pairs, the cables 37 and 39 being fixed together and the cables 38 and 40 being fixed together. The cables 39 and 40 continue rearwardly, each making a half turn about the re-

spective pulleys 65 and 66, are brought forward and fixed respectively in holes 70 and 71 of the cross head 72 of hydraulic ram 75.

For operating ram 75 we provide the pump 135, 5 (which is driven by a clutch through certain shafts, sprockets and chains by the motor which drives the tractor) storage tank 141 and three-way valve 140, this valve being positioned convenient to the operator's seat whereby he can 10 at will operate the ram 75 and thus raise or lower the hood 36 with its combustion chamber.

For supplying fuel oil from fuel tank 35 to the fuel nozzle 123 we provide a force pump 130 which is driven, in a similar manner to pump 135, 15 from the tractor motor. Pump 130 being provided with a spring by-pass valve automatically maintains a constant pressure on the discharge side of the pump.

To supply a volume of air to complete the combustion of oil in the fire box 41 we have provided a blower 180, which is driven by belt 183 from the shaft which drives pump 130. This blower 180 is connected with fire box 41 by the large pipe 185 which has a flexible portion 186 on account of raising and lowering the hood 36.

To place the machine in operation the various tanks are filled with oil and with the hood resting on the street surfaces the tractor motor is started. The clutch, which drives the pumps 130 and 135 30 and the blower 180, is engaged, the burner in the fire box is lighted, and the fuel and air are adjusted to obtain proper combustion. The air and fuel inlets entering the combustion chamber at an angle as shown in Figures 3 and 4 cause a 35 thorough mixing of the air and fuel (preferably fuel oil) and the flame is thereby given a rotary movement within the combustion chamber 41 causing thorough combustion. The hot gases thus created flow out of the fire box 41 through the opening 43 against the spreader plate 50 and thence through the spaces between the spreader 40 plate 50 and the hood plates 44 away from the area directly beneath the spreader plate 50 but heat from the spreader plate 50 is radiated against the street surface directly beneath the spreader 45 plate so that the full area of street surface beneath the hood 36 is heated. When this area is sufficiently heated the hood is lifted by operating the three-way valve 140 which controls the flow 50 of oil from pump 135 to ram 75 thus raising the hood 36. The tractor is then thrown in gear and the machine is moved to another area to be heated, the hood is then lowered by operating the three-way valve 140 in the reverse direction, 55 thus lowering the hood until it rests on the street surface, bringing the hot gases in contact with another area to be heated.

When moving the machine considerable distances it is not desirable to carry the weight of the hood by the pressure of the oil in the ram 60 75 therefore we have provided a hook 81 which, when the hood is at its highest position, engages the tooth 82 on crosshead 72, thereby supporting the weight of the hood 36.

From the foregoing description it can be seen that the use of the machine covers its application to long stretches of old pavement to be removed as well as to patching spots irregularly scattered. Many modifications of the machine 5 may be made without departing from the spirit and scope of our invention, we therefore wish to include all such as come within the scope of the appended claims.

We claim:—

1. In a road heating machine, the combination of a supporting frame, a hood vertically adjustably suspended therefrom, a circular combustion chamber rigidly secured to said hood and adapted to discharge directly into the hood and 10 means for supplying air and fuel to said combustion chamber.

2. In a road heating machine, the combination of a supporting frame, a hood suspended therefrom comprising a member forming a cavity, a circular combustion chamber secured to said hood and adapted to discharge hot gases into said 15 cavity and a baffle plate in the form of an inverted cone positioned in said hood in the path of the discharge from said combustion chamber. 25

3. In a road heating machine, the combination of a supporting frame, a hood suspended therefrom, means for vertically adjusting said hood, a circular combustion chamber formed integral with said hood, a heat insulating lining 30 within said chamber and a discharge port leading from said chamber communicating with said hood.

4. A surface heater comprising a flexibly suspended hood, a circular combustion chamber secured thereto, an insulated inner wall for said chamber, separate fuel and air inlets passing through said wall at an angle whereby the fuel and air discharged into said chamber will be given a rotary movement therein, and a discharge passage between said chamber and the interior of said hood. 35

5. A surface heater comprising an adjustable hood, a substantially circular combustion chamber secured to said hood, said chamber having 45 an inner wall of insulating material, separate air and fuel inlets communicating with said combustion chamber, a discharge passage between said chamber and the interior of said hood and a baffle plate adjacent said passage so positioned in said hood that a change in direction of motion of hot gases issuing from said passage is effected. 50

6. A surface heater comprising a movable hood open at the bottom and having an aperture in its upper surface, a combustion chamber resting upon said hood, said chamber lined with heat resistant material, a hollow annular member between said combustion chamber and the interior of said hood forming a passage between the chamber and the hood and a baffle plate of inverted pyramidal form positioned below said passage. 55
